UNITED STATES PATENT OFFICE.

JOHN IHRIG, OF ROCHESTER, NEW YORK.

COOLING DEVICE.

1,170,641.

Specification of Letters Patent.

Patented Feb. 8, 1916.

Application filed May 1, 1913. Serial No. 764,798.

To all whom it may concern:

Be it known that I, JOHN IHRIG, of Rochester, in the county of Monroe and State of New York, have invented certain new and 5 useful Improvements in Cooling Devices; and I do hereby declare the following to be a full, clear, and exact description of the same, reference being had to the accompanying drawings, forming a part of this specification, and to the reference-numerals marked thereon.

My invention relates to cooling devices for use in cold storage plants and similar places, and it has for its object to provide a portable 15 apparatus that will effectively cool a cold storage room, the parts being constructed and arranged so as to effect a very large saving in the amount of ice consumed, for any given amount of cold produced. That is to 20 say, with my improved apparatus, it is possible to produce a maximum amount of cold from a minimum supply of ice.

A further purpose of my invention resides in providing in the same apparatus a freezing or refrigerating chamber, for fowl or other small meats and the like, without increasing to any substantial extent the amount of ice that would otherwise be consumed.

Still another object of my improvement 30 consists in affording such a construction that the different parts are readily accessible for cleaning, and the supply of ice may be replenished as often as necessary with considerable ease.

To these and other ends the invention consists in certain improvements and combinations of parts all as will be hereinafter more fully described, the novel features being pointed out in the claims at the end of the 40 specification.

In the drawings: Figure 1 is a side elevation of an apparatus constructed in accordance with a preferred embodiment of the invention; Fig. 2 is a transverse sectional view; Fig. 3 is a longitudinal sectional view, and Fig. 4 is a horizontal sectional view.

Similar reference numerals in the several figures indicate the same parts.

The invention, as illustrated in the present embodiment, preferably comprises a casing supported on the frame 1 and provided with double walls 2, which consist of inner and outer partitions that serve to retain the cold within the casing and to prevent entrance of the hot air from the outside through the walls of the casing, all of which

tends to effect a saving in the amount of ice consumption.

Within the casing there is arranged an ice chamber designated at 3, which is disposed in spaced relation to the walls of the casing so as to afford a passage all around for the currents of air, as will be more fully described hereafter.

The ice chamber 3 is intended to be filled with crushed or broken ice, as indicated at 4, and in order to permit the ice chamber to be readily filled, it is provided with a removable cover constructed in two sections 5 and 6 respectively, which may be connected in the manner shown in Fig. 3.

Disposed beneath the ice chamber are a series of refrigerating or freezing compartments 7 which are designed to receive small articles of meat and similar goods that must be kept very cold, and at or near freezing temperatures, said compartments being accessible through the doors 8, and adapted to be maintained at the desired temperatures by the means that I will now describe. To this end, a cooling coil 9 is provided which extends around three sides of the compartment section and is connected with an overflow trough gutter 10 disposed at the bottom of the ice chamber, to receive the brine and melted ice as it flows out from the ice chamber, the latter being provided with outlet pipes 11 at the bottom thereof for this purpose. The lower end of the cooling coil 9 which is indicated at 12, may be connected with any suitable discharge, through which the water is carried off from the apparatus.

In order to induce a circulation of air about the ice chamber and between it and the walls of the casing, I provide above the ice chamber suitable air current producing means, preferably in the form of an electrically operated fan 13 which is mounted on a suitable support 14. I have found that the best results are obtained when the fan 100 is directed upwardly at a slight angle as shown at Fig. 3, although this arrangement may be varied without changing the essential principles of the invention, and in order to deflect and break up the currents produced by the fan, there is provided an adjustable baffle 15, which is preferably hinged as shown, and may be held in any one of several positions by means of the movable support 16 which is adapted to engage the projections 17 on the cover of the ice chamber. By this means, the air is

thrown forcibly against the baffle 15 by which a part of it is directed upwardly, while a sufficient amount passes to both sides of the baffle in a downward direction, going 5 around the walls of the ice chamber until it is discharged at the bottom of the casing. A continuous circulation of this kind is kept up, the air in the room or compartment in which the apparatus is placed being 10 thus constantly cooled and freshened. Owing to the arrangement of the ice chamber in spaced relation to the walls of the casing, in connection with the means for inducing a current of air continuously in a 15 downward direction about the casing, I am able to maintain the air in the room at a sufficiently low temperature for the purposes required, with a comparatively small expenditure of ice.

20 It is desirable that none of the air be forced in a direction laterally of the apparatus into the room, lest it may strike directly upon some of the meats or other goods, and to this end there is preferably 25 provided a hood 18 at the top of the casing, which extends entirely around the apparatus and is high enough to inclose the fan 13, as shown in Fig. 3, so that any forced currents of air that are induced by the 30 fan, move either downwardly through the apparatus or in a direction upwardly

through the hood, being discharged at the top or bottom.

I claim as my invention:

1. A cooling apparatus comprising a casing 35 open at the bottom, a closed ice chamber arranged within the casing in spaced relation to the walls thereof, a refrigerating compartment arranged beneath the ice chamber, a cooling coil surrounding the refrigerating compartment and communicating with the ice chamber, and air circulating means disposed above the ice chamber and acting to direct currents of air downwardly between the walls of the chamber 40 and casing and discharge it at the bottom of the casing.

2. A cooling apparatus comprising a casing 50 open at the bottom, a closed ice chamber arranged within the casing in spaced relation to the walls thereof, a refrigerating compartment disposed beneath the ice chamber, an overflow gutter surrounding the bottom of the ice chamber, and a cooling coil 55 surrounding the refrigerating compartment and communicating with said overflow gutter.

JOHN IHRIG.
